UNITED STATES PATENT OFFICE.

ADRIAN C. SCHARFF, OF ORANGE, CONNECTICUT.

DESIGN FOR AN ASH RECEPTACLE.

Application filed April 13, 1926. Serial No. 17,279. Term of patent 3½ years.

To all whom it may concern:

Be it known that I, ADRIAN C. SCHARFF, a citizen of the United States, residing at Orange, county of New Haven, State of Connecticut, have invented a new, original, and ornamental Design for an Ash Receptacle, of which the following is a specification, reference being had to the accompanying drawing, forming part thereof.

Fig. 1 is a side elevation of an ash receptacle showing my new design.

Fig. 2 is a top plan view thereof.

Fig. 3 is a front end elevation, and

Fig. 4 is a rear end elevation.

I claim:

The ornamental design for an ash receptacle substantially as shown.

ADRIAN C. SCHARFF.
